UNITED STATES PATENT OFFICE.

LOUIS A. HAWTHORNE, OF NEWARK, NEW JERSEY, ASSIGNOR TO STEEL UTILITIES,
INCORPORATED, A CORPORATION OF NEW YORK.

METAL-PUNCHING MACHINE.

1,241,255.

Specification of Letters Patent. Patented Sept. 25, 1917.

Application filed April 28, 1914. Serial No. 834,908.

To all whom it may concern:

Be it known that I, LOUIS A. HAWTHORNE, a citizen of the United States, and resident of Newark, in the county of Essex, State of New Jersey, have invented new and useful Improvements in Metal-Punching Machines, of which the following is a specification.

The invention relates to metal punching machines and more particularly to machines for punching structural shapes, and in certain aspects of the invention, it relates more particularly to machines for punching beam flanges. Further objects of the invention will in part be obvious and in part will appear hereinafter.

The invention consists in the novel parts, constructions, combinations and improvements herein shown and described.

The accompanying drawings, referred to herein and forming a part hereof, illustrate one embodiment of the invention, and together with the description serve to illustrate the principles thereof.

Of the drawings:

Figure 1 is a transverse vertical section through the machine (on line E—F of Fig. 3);

Fig. 2 is an end elevation looking at Fig. 1 from the left (with internal parts omitted);

Fig. 3 is a full vertical section on the line C—D of Fig. 1 looking to the left;

Fig. 4 is an enlarged fragmentary central view, with parts in section and other parts in elevation, of the central part of Fig. 1, but showing the mechanism operating upon a larger beam;

Fig. 5 is a similar view to Fig. 4 but showing the parts in different positions;

Fig. 6 is a vertical section on the line G—H of Fig. 5, looking to the left;

Fig. 7 is a fragmentary view in elevation of the beam centering devices shown at the left in Fig. 3;

Fig. 8 is a section on the line A—B of Fig. 3, showing certain parts in elevation; and

Fig. 9 is a section on the line I—K of Fig. 4.

Fig. 10 is a fragmentary detail of the punch and gag operating mechanism;

Fig. 11 is a perspective of the wedge operating mechanism; and

Fig. 12 is a fragmentary plan of the sleeve for the interponents and coöperating parts.

Referring to the accompanying drawings, illustrating by way of example one embodiment of the invention, means are provided for traveling and stopping a shape relatively to the punching mechanism to properly locate the perforations in the shape, and said traveling and stopping devices are preferably under the control of settable distance determining devices, an embodiment of such devices being illustrated and described in application Ser. No. 814,380, of T. P. Payne, filed January 26, 1914. Said devices are not shown in detail herein, but the forwarding rollers 1 travel the beam along its pathway past the punching mechanism, and the head 2, against which the forward end of the shape α abuts as it is impelled forward by the rollers 1 is connected to the rack bar 3, which rack bar is connected to and controlled by the distance determining devices not shown in detail in this case.

Means are provided by the invention whereby the two flanges of the beam are simultaneously punched in accordance with the indications of the distance determining devices. According to certain features of the invention means are provided also which simultaneously operate the punches for both flanges of the beam. As embodied said means are operated hydraulically, although so far as concerns certain other features of the invention other than hydraulic means could be used to operate the punches.

In the embodied form a suitable supporting frame is provided, comprising vertical frame plates 10 and 11, which plates are tied together by cross frame plates 12 and 13. The plates 10 and 11 are centrally apertured to permit the beam α to travel through. Mounted upon the plates 10 and 11 are horizontally arranged guideways, a pair of guideways 14 and 15 being arranged one above the other on the plate 10, and an opposed pair of guideways 16 and 17 being mounted one above the other upon the plate 11. Supported and guided by said guides 14, 15, 16 and 17 are two cross heads 18 and 19, which support various parts of the punching mechanism, and are movable together and also relatively to each other for purposes hereinafter described.

Upon the cross head 19 is mounted the punches for one of the shape flanges, being the right hand one referred to Fig. 1. The punches 20 and 21 are carried in the supporting block 22 fixed to or integral with the

cross head 19. Said punches 20 and 21 reciprocate in guiding apertures in blocks 23 and 24. The block 23 is carried on a support 25 and has a dovetail connection therewith whereby the blocks 23 are replaceable, and the block 24 is similarly carried on a support 26. The support 25 is slidably mounted upon a shaft 27, the support 25 being slidable along the shaft horizontally (referred to Fig. 1), and the shaft and support being movable to and fro vertically. For this purpose, the shaft 27 is mounted on links 34, carried by arms 28 and 29, fixed to a shaft 30 journaled on the machine frame. A suitable counter-balance is provided comprising an arm 31 fixed to said shaft and weights 32 supported by arm 31. The die block 24 is mounted on a support 26, which is similarly slidably mounted on shaft 33 horizontally (referred to Fig. 1). The shaft and support are likewise vertically movable together, the shaft 33 being carried by links 35, pivotally connected to arms 36, which arms are fixed to a shaft 37 journaled on the machine frame. A suitable counterbalance is provided, comprising an arm 38, fixed to shaft 37, said arm carrying weights 39.

Similar die blocks 40 and 41 are provided for the opposite flange of the web. The block 40 is carried by a dovetail connection on a support 42, which support is slidably mounted on shaft 27. The block 41 has likewise a dovetail connection with a support 43, slidably supported on shaft 33. The various die blocks are suitably apertured to permit the punchings to drop away therefrom.

Means are provided by the invention for moving the die blocks together or independently both to separate the blocks or to draw them together vertically, referred to Fig. 1, and to move them together, vertically, referred to Fig. 1, to change their center. In the embodied form of such means, a suitable drive is provided, such as a motor 44 driving a shaft 45, carrying a worm 46 (Figs. 3, 7 and 8). Said worm engages a worm wheel 47 splined on a vertical shaft 48, which shaft is carried in supporting blocks 49 and 50 on the frame, said shaft 48 being vertically slidable in said blocks. The shaft 48 is threaded right and left. A nut 51 on shaft 48 connects to a pin 52 which pin passes through the die block 41. The head of the pin 52 fits in a block which works in a slot 53 formed in arms fixed to nut 51, thereby permitting horizontal movement of the block 41 relatively to the nut 51. A similar nut 54 is on the other thread on shaft 48, and has similar connection with a pin 55, passing through die block 40. Fast to pin 52 is a bell crank lever 56, having a horizontal arm adapted to engage the upper edge 65 of the beam flange, the other arm 57 of said

bell crank being slotted and extending downwardly. Fixed to pin 55 is a corresponding bell crank lever 58, with a horizontal arm adapted to engage the lower end of the beam flange. The other arm 59 of 70 said bell crank is slotted and extends upwardly past the slotted arm 57 of bell crank 56. Passing through the slots in arms 57 and 59 of the two bell crank levers is a pin 60. The pin 60 is fixed to a bifurcated slide 75 61, straddling shaft 48 and slidably supported by collars 62 and 63 on said shaft. In an aperture in slide 61 works a pin 64 fixed to a rod 65 slidable in a support 66 on the machine frame. Fixed to rod 65 is 80 a plunger 67 working in a cylinder 68, and acted on by a suitable pressure fluid. A suitable pipe 69 connects to the main valve for the punch. A suitable restoring spring 70 acts on rod 65. A support 71 limits the 85 downward movement of nut 54 to a position corresponding to the bottom edge of the fed-in beam flange.

The manner of operation of the mechanism just described is substantially as follows:

The motor 44 is controlled preferably from a distance record strip, such as is shown in copending application Ser. No. 814,380, filed Jan. 26, 1914. As shaft 48 95 rotates (considering the device as being set for a new size of beam) driven by motor 44, nuts 51 and 54 will travel toward each other. Nut 54 rests on support 71, and this causes shaft 48 to descend and nut 51 to 100 descend also relatively to the shaft. When lever arm 56 engages the upper edge of the beam flange, lever arm 58 is also brought into engagement with the lower edge of the beam flange. The slide 61 also moves correspondingly relatively to pin 64, which slides in the slot in slide 61. When the pressure is put on cylinder 68, the rod 65 and pin 64 are moved to the left in Fig. 7 and the slide 61 also being moved to the 110 left causes the lever arms 56 and 58 to grip the beam flange. Preferably pipe 69 is connected to the main operating valve for the punch, and in such case, when the pressure is turned on the main valve, the 115 plunger 67 being lighter, the clamping action of arms 56 and 58 just precedes the punching operation. The clamping of the beam flange, through the movement imparted to pins 52 and 55 brings the punch 120 and die blocks to center or proper position for punching. As the die blocks 40 and 41 are centered, they move the corresponding shafts 27 and 33 up or down and thus also center the die blocks 23 and 24 for the other 125 beam flange, together with their punches. The various punches work in apertures in the die blocks, as will be later more fully described, and are thus centered with them. The clamping and centering occurs at every 130

punching operation, but the adjustment for size need be effected only at a change in the size of beam operated upon. When a larger size of beam is to be taken in, the motor 44 is run in the opposite direction, and the nuts 51 and 54 travel slightly apart. The nut 54 coming to rest on support 71, the shaft 48 is moved upwardly until the mechanism is brought to position preparatory to 10 receiving the new beam.

Means are provided by the invention for positioning the punches and die blocks for beams of different depths or sizes. In the embodied form of such means, the right hand die block and punches are traveled horizontally (referred to Fig. 1). Upon the cross head 19 is carried a punching head 80. In said head 80 are one or more slots 81 into which project the heads 82 of the 20 punches 21 and 22, (Figs. 1 and 10), the punch heads 82 being mounted in the die blocks 23 and 24 to reciprocate in punching the work. Gags or interponents are provided for selectively operating the punches, 25 and as embodied (Fig. 10) cross slots 83 are formed in the head 80 in which slots 83 reciprocate gags 84. The gags 84 have beveled ends 85 adapted to pass beneath or 30 behind the heads of the punches as the gag 35 slides into position behind the punch. The gags 84 have rods 86 connected to actuating levers 87, whereby the gags are slid into and out of operative position with respect to their punches. The levers 87 are actuated 40 by solenoids 87^a controlled from the distance record strip such as is shown in said copending application, Ser. No. 814,380, or they may be actuated manually if desired. The left hand punching head 88 (referred 45 to Fig. 1) is fixed to the plunger of the actuating cylinder. The punching head 88 is provided with punches 21 and 22, and with gags and other coöperating parts, similarly to the head 80 already described.

45 The cylinder 89 is carried on cross head 18, the plunger 90 working within the cylinder, and the pressure fluid being admitted and exhausted through conduit 91. Fixed to cylinder 89 are upwardly and downwardly 50 projecting brackets 92 and 93. Upon the cross head 19 are corresponding upwardly and downwardly projecting brackets 94 and 95. Mounted to rotate in bracket 93 is a shaft 96, and said shaft has screw thread 55 engagement with bracket 95. A shaft 97 is similarly rotatably carried by bracket 92 and has similar screw-thread engagement (not shown) with bracket 94. The shafts 96 and 97 are driven in unison by suitable 60 means such as sprocket wheels 98 and 99, mounted on the respective shafts, and having a sprocket chain 100.

A suitable drive is provided, and in accordance with one feature of the invention, 65 means controlled by the automatic distance

record, previously referred to, are provided and such means as embodied comprise a motor 101. Motor 101 drives by means of a sprocket chain 102, a friction drive, which operates a solenoid controlled positioning 70 wheel or disk 104, which connects by a sprocket chain 105 to one of the shafts 96 or 97. The solenoids 106 may be connected to the distance record device and be controlled thereby. 75

Means are provided for bringing the die blocks firmly against the flanges preparatory to punching. As embodied, wedges 115 and 116 are forced in between the respective pairs of die blocks, the wedge 115 forcing 80 the die blocks 24 and 41 apart and firmly against the inside of the beam flanges. The wedge 116 operates in a similar manner between the die blocks 23 and 40. In the embodied form of means for operating the 85 wedges, said wedges are formed with legs 117 and 118 extending back from the body of the wedges and within the hollow interior of the die blocks 25 and 26. Pivoted to legs 117 and 118 are links 119 and 120. 90 The wedges 116 are reciprocable in guides 121 in the respective die blocks. Connected to links 119 and 120 is a yoked lever 122 also positioned within the hollow die blocks 25 and 26, which lever 122 connects across from 95 one side of the machine to the other, and also to the actuating means. Yoked lever 122 has arms 123 and 124, connecting respectively to links 119 and 120, and has a downwardly bent connecting yoke 125, and an upwardly extending arm 126. Lever 122 is pivotally mounted at 127 and 128, and is actuated by means of a fluid pressure cylinder 130. Cylinder 130 is mounted on cross-head 19. The piston rod 131 of said cylinder connects by a pivoted link 132 with arm 126 of lever 122. Cylinder 130 is provided with ports 133 and 134, connecting to suitable 100 valve controls with a source of pressure fluid supply. As embodied, the port 133 is under constant or continuous pressure and the port 134 is connected to the main operating valve of the punch. Springs 135 act to move die blocks 40 and 41 slightly to the right (referred to Fig. 1) to receive each new beam 105 and act as a cushion for the action of wedges 116. 110

The invention provides, in accordance with one of its features, for varying the size of the wedges for beams of different depths 120 or sizes, and in accordance with one feature of the invention, such variation in size of the wedges is automatically effected. As embodied, a plurality of auxiliary wedge members are provided which are automatically 125 presented by the machine in requisite number for interposition with the wedges 116 between the die blocks for the two flanges. In the embodied form, a set of such interponents or fillers 136 is provided for both 130.

sides of the beam and may be the same or similar in construction. The carriers 42 and 43 are hollow, the interponents 136 being located therewithin.

- 5 When in the inoperative position, the interponents are supported on horizontal guides 137 and 138 formed on the inner vertical walls of the carriers 42 and 43. The interponents 136 are cut away centrally into 10 yoke shape with the central part extending downwardly (Figs. 1, 4, 5 and 6). In said central cutaway portion is a sleeve 139 having at either end collars 140 and 141 which prevent longitudinal displacement of 15 the interponents from the sleeve. The interponents are removable vertically by means to be described. Slidable on vertical guides 142 on the frame plates 10 and 11 are frames 143, two above and two below (Fig. 1) for 20 each set of interponents, and each having vertical arms 144 and 145 and at the bottom a horizontal connecting face or reach 146, provided with guides 147 and 148, adapted to receive the interponents from the 25 guides 137 and 138 of the supports 42 and 43 (Figs. 1 and 6). The frames 143 are vertically slidable to carry the interponents from the inoperative or supply position into 30 position between the die blocks. 35 The frames 143 are operated by means of pins 149 (which also serve as pivot points between links 119 and 120 and yoke lever 122). The pins 149 project through curved slots 150 in both sides of the die block carriers 25 and 26, and into slots 151 in the cross or horizontal reaches of the respective frames 143. The frames 143 thereby have a vertical movement (referred to Figs. 1, 4, 5 and 6) whereby their guides 147 and 148 40 for the interponents pass into alinement with guides 137 and 138 to receive from and to return to the latter the requisite number of the interponent units, and in the intervening time frames 143 carry the interponents down 45 between the die blocks to coöperate with the wedges 115 and 116 while the flanges are being punched.

Means are provided for keeping the interponents to position, and as embodied, the 50 collar 141 is loose upon sleeve 139. A spring 152 is coiled about sleeve 139 and works between loose collar 141 and a fixed collar 153. The downward travel of the interponents when carried by frames 143 is such that the 55 interponents on the frames have their ends still in horizontal alinement (Figs. 1 and 6) with the interponents remaining on the guides 137 and 138 of the supports 42 and 43, and thus prevent the interponent units 60 passing or interfering with each other.

Means are provided for presenting the proper number of interponents dependent upon the degree of separation of the die blocks and the depth or size of the beam to 65 be punched. In the embodied form, the

upper and lower sleeves 139 are splined on their respective shafts 96 and 97 to rotate therewith while free to slide therealong. At their right hand ends (Figs. 1 and 12) the sleeves 139 are externally screw-threaded. 70 Such screw-threaded portions 154 engage nuts 155, which have wings 156 which engage the frame plates 10 and 11, and prevent the nuts from turning.

In accordance with one feature of the invention, there is incorporated with the foregoing means, as embodied, devices for easing away die blocks 23 and 24 from the work. Such devices comprise angle plates 157 fixed to frame plates 10 and 11, and having rods 158 and 159 fixed thereto, respectively, and extending through apertures in the corresponding wings 156 of nuts 155. Springs 160 are coiled about bolts 158 and 159 and are in compression between the heads of bolts 158 and 159 and the wings 156 of nuts 155. The springs are sufficiently strong to prevent movement of the nuts 155 except when the wedges are inserted or withdrawn. The collars 140 serve not only 90 to hold the interponents 136 on the sleeve but also connect the sleeves 139 and the supports 25 and 26 for the die blocks 23 and 24.

Suitable restoring means for bringing the 95 cylinder 89 and plunger 90 back to position after the punching operation are provided, and as embodied, wings 162 are fixed to plunger 90. Fixed to wings 162 are rods 163, extending through pockets 164 fixed 100 relatively to cylinder 89. Springs 165 are coiled around rods 163 and are in compression between the ends of pockets 164 and nuts 166 on the ends of rods 163. A stop 167 acts against one of the wings 162. 105

The manner of operation of the mechanisms described will be clearly understood from the statements and explanations made in connection with the various groups of mechanism. It may be generally stated, 110 however:

The die blocks are centered and positioned or gaged to properly locate the punch holes in the flanges, as already described. In positioning the mechanism for the depth of 115 the beam (that is, horizontally in Fig. 1), only the right hand die blocks 23 and 24 are traveled. This travel is effected by the rotation of shafts 96 and 97, from motor 101, controlled by the distance record sheet, 120 or otherwise. The cross head 19 is thus traveled to the right or left in Fig. 1, and the die blocks 23 and 24, and their respective supports 25 and 26 travel therewith, the supports sliding on rods 27 and 33 125 (through which rods they receive their vertical positioning as already described). The supports are slid along the rods by their connection through yokes 122 and cylinders 130, the pins 149 being held in the ends of 130

slots 150 and 151 by the pressure on the cylinders 130, the pistons being at the right hand end of the cylinders (Fig. 1) at this time. Thus beams of varying depths are received with their flanges in the recesses of the four die blocks, and the die blocks also having been vertically centered and positioned as already described. The travel of the beam longitudinally through the machine and its stopping to properly locate successive punchings along the beam or shape are effected by the head 2 and rack bar 3, which head and bar are controlled by the distance determining device. Said device may be controlled by a distance record strip or a keyboard, or otherwise. The wedges 115 and 116 are driven in between the corresponding pair of die blocks (considered horizontally of Fig. 1) by the pressure being admitted through ports 134 into cylinders 130, which drives the pistons and their rods 131 to the left in Fig. 1. This swings yoke levers 122 and drives in the wedges 115 and 116. Frames 143 are all slid inwardly at the same time, through the engagement of pins 149 in slots 151 in cross pieces 146 of the frames 143. If supports 25 and 26 have been moved to the right sufficiently (dependent on the size of the beam to be operated upon) one or more of the interponents 136 have been moved from the guides 137 and 138 on supports 42 and 43 onto the guides 147 and 148 on frames 143, by reason of sleeves 139 also traveling to the right with supports 25 and 26. Thus the required number of interponents are interposed or driven in together with the wedges, to firmly draw the die blocks against the inner faces of the beam flanges, acting against springs 135 and 160.

The punching is effected on the clamped beam by the fluid pressure entering cylinder 89. The plunger 90 advances to the right (Fig. 1) until the punches carried thereby are against the beam flange, and the cylinder is moved to the left (in Fig. 1) until the punches carried by the opposite die blocks (at the right Fig. 1) are thereby brought against the opposite beam flange. The fluid pressure is then exerted against both the cylinder 89 and the plunger 90 to effect the punching of the beam flanges. Suitable slots are made in the die blocks to discharge the punchings. As embodied, the pressure in the cylinder 130 is accumulated or built up prior to the punching cylinder and plunger being brought into action, and they may thereby be operated and controlled from and by a single valve. This valve may be in turn controlled or operated automatically from a distance record strip or like device.

After the punching, the controlling valve is reversed, automatically or otherwise, exhausting the pressure. The cylinder 89 and plunger 90 are returned to initial position

by action of springs 165 as already described, and all the punches are thereby withdrawn from the punched holes in the flanges. The pressure in ports 134 has also been cut off and the pressure in ports 133 acts to move the pistons and piston rods 131 to the right (Fig. 1) withdrawing wedges 115 and 116 and also moving away frames 143 and thus likewise withdrawing interponents 136. The easing of the die blocks back from the flanges has already been described. The lever arms 56 and 58 are also rocked apart, thereby unclamping the beam, as already described. The beam or shape is free to be traveled forward and positioned for the next punching in accordance with the setting of the distance determining device.

It will be understood that changes may be made from the actual mechanisms shown and described, without departing from the principles of the invention, and without sacrificing its chief objects and advantages.

What I claim is:

1. A machine for punching structural shapes including in combination means for supporting shapes of various sizes, punch and die mechanism for punching the shape flanges, and means for centering the punch and die mechanism relatively to shapes of different sizes.

2. A machine for punching structural shapes including in combination means for supporting shapes of various sizes, punch and die mechanism for punching the shape flanges, and means acting automatically to center the punch and die mechanism toward and from the support for shapes of different sizes.

3. A machine for punching structural shapes including in combination means for supporting shapes of various sizes, punch and die mechanism for punching the shape flanges, and means controlled by a distance record device for centering the punch and die mechanism relatively to shapes of different sizes.

4. A machine for punching structural shapes including in combination means for supporting shapes of various sizes, punch and die mechanism for punching the shape flanges, and means for centering the punch and die mechanism transversely to the shape for shapes of different sizes.

5. A machine for punching structural shapes including in combination means for supporting shapes of various sizes, punch and die mechanism for punching the shape flanges, and means controlled by a distance record device for centering the punch and die mechanism vertically relatively to shapes of different sizes.

6. A machine for punching structural shapes including in combination means for supporting shapes of various sizes, punch

and die mechanism for punching the shape flanges, means for centering the punch and die mechanism relatively to shapes of different sizes, and means for traveling and stopping the shape at various desired positions to be punched.

7. A machine for punching structural shapes including in combination means for supporting shapes of various sizes, punch and die mechanism for punching the shape flanges, and means controlled by a distance record device for centering the punch and die mechanism for shapes of different sizes, and means for successively traveling and stopping the shape at various positions in accordance with the indications of the distance record device.

8. A machine for punching structural shapes including in combination means for supporting shapes of various sizes, punch and die mechanism for punching the shape flanges, means for centering the punch and die mechanism vertically for shapes of different sizes, and means for traveling and stopping the shapes at various desired positions to be punched.

9. A machine for punching structural shapes including in combination means for supporting shapes of various sizes, punch and die mechanism for punching the shape flanges, and means controlled by a distance record device for centering the punch and die mechanism vertically for shapes of different sizes, and means for successively traveling and stopping the shape at various positions in accordance with the indications of the distance record device.

10. A machine for punching structural shapes including in combination means for supporting a shape, a plurality of punches and dies for punching a flange of said shape, and means for moving said punches and dies together or apart to symmetrically position the punches on either side of the web.

11. A machine for punching structural shapes including in combination means for supporting a shape, a plurality of punches and dies for punching a flange of said shape, and means controlled by a distance record device for moving said punches and dies together or apart to symmetrically position the punches on either side of the web.

12. A machine for punching structural shapes including in combination means for supporting shapes of various sizes, punches and dies for punching a flange, and means for centering the punches and dies for various sizes of shapes, and for moving the punches and dies together and apart to symmetrically position the punches and dies on either side of the web.

13. A machine for punching structural shapes including in combination means for supporting shapes of various sizes, punches

and dies for punching a flange, and means acting automatically to center the punches and dies transversely to the shape for various sizes of shapes, and for moving the punches and dies together and apart to symmetrically position the punches and dies on either side of the web.

14. A machine for punching structural shapes including in combination means for supporting shapes of various sizes, punches and dies for punching a flange and means controlled by a distance record device for centering the punches and dies for various sizes of shapes, and for moving the punches and dies together and apart to symmetrically position the punches and dies on either side of the web.

15. A machine for punching structural shapes including in combination means for supporting shapes of various sizes, punches and dies for punching a flange, means for centering the punches and dies for various sizes of shapes, and for moving the punches and dies together and apart to symmetrically position the punches and dies on either side of the web, and means for traveling and stopping the shape to be punched at various desired positions.

16. A machine for punching structural shapes including in combination means for supporting shapes of various sizes, punches and dies for punching a flange, means for centering the punches and dies for various sizes of shapes, and for moving the punches and dies together and apart to symmetrically position the punches and dies on either side of the web, and means for traveling and successively stopping the shape to be punched in accordance with the indications of the distance record device.

17. A machine for punching structural shapes including in combination means for supporting a beam on the flange edges, punch and die mechanism for punching the beam flanges, and means for centering the punch and die mechanism relatively to the webs of different size beams.

18. A machine for punching structural shapes including in combination means for supporting a beam on the flange edges, punch and die mechanism for punching the beam flanges and means operating automatically moving the punch and die mechanism toward and from the support to center same relatively to the webs of different size beams.

19. A machine for punching structural shapes including in combination means for supporting a beam on the flange edges, punch and die mechanism for punching the beam flanges, and means controlled by a distance record device to center the punch and die mechanism relatively to the webs of different size beams.

20. A machine for punching structural shapes including in combination means for

- supporting a beam on the flange edges, punch and die mechanism for punching the beam flanges, means for centering the punch and die mechanism relatively to the webs of different size beams, and means for traveling and successively stopping the beam to be punched at various desired positions. 5
21. A machine for punching structural shapes including in combination means for supporting a beam on the flange edges, punch and die mechanism for punching the beam flanges, and means controlled by a distance record device to center the punch and die mechanism relatively to the webs of different size beams, and means for traveling and successively stopping the shape to be punched in accordance with the indications of the distance record device. 10
22. A machine for punching structural shapes including in combination means for supporting a beam on the flange edges, punch and die mechanism for punching the beam flanges, and means for moving the punches and dies together or apart to symmetrically position the punches on either side of the web. 15
23. A machine for punching structural shapes including in combination means for supporting a beam on the flange edges, punch and die mechanism for punching the beam flanges, and means controlled by a distance record device to move the punches and dies together or apart to symmetrically position the punches on either side of the web. 20
24. A machine for punching structural shapes including in combination means for supporting shapes of various sizes, punch and die mechanism for punching the shape flanges, means for centering the punch and die mechanism for shapes of different sizes, means for traveling and stopping the shape at various desired positions to be punched, and means for clamping the shape prior to and unclamping it after each punching operation. 25
25. A machine for punching structural shapes including in combination means for supporting shapes of various sizes, punch and die mechanism for punching the shape flanges, means acting automatically to move the punch and die mechanism transversely to the shape to center same for shapes of different sizes, means for traveling and stopping the shape at various desired positions to be punched and means for clamping the shape prior to and unclamping it after each punching operation. 30
26. A machine for punching structural shapes including in combination means for supporting shapes of various sizes, punch and die mechanism for punching the shape flanges, means controlled by a distance record device for centering the punch and die mechanism for shapes of different sizes, 35
- means for successively traveling and stopping the shape at various positions in accordance with the indications of the distance record device, and means for clamping the shape prior to and unclamping it after each punching operation. 70
27. A machine for punching structural shapes including in combination means for supporting shapes of various sizes, punches and dies for punching a flange, means for centering the punches and dies for various sizes of shapes, and for moving the punches and dies together and apart to symmetrically position the punches and dies on either side of the web, means for traveling and stopping the shape to be punched at various desired positions, and means for clamping the shape prior to and unclamping it after each punching operation. 75
28. A machine for punching structural shapes including in combination means for supporting shapes of various sizes, punches and dies for punching a flange, means for centering the punches and dies for various sizes of shapes, and for moving the punches and dies together and apart to symmetrically position the punches and dies on either side of the web, means for traveling and successively stopping the shape to be punched in accordance with the indications of the distance record device, and means for clamping the shape prior to and unclamping it after each punching operation. 80
29. A machine for punching structural shapes including in combination means for supporting a beam on the flange edges, punch and die mechanism for punching the beam flanges, means for centering the punch and die mechanism relatively to the webs of different size beams, means for traveling and successively stopping the beam to be punched at various desired positions, and means for clamping the shape prior to and unclamping it after each punching operation. 85
30. A machine for punching structural shapes including in combination means for supporting shapes of various sizes, punch and die mechanism for punching the shape flanges, means for centering the punch and die mechanism for shapes of different sizes, and means for clamping the shape preparatory to punching. 90
31. A machine for punching structural shapes including in combination means for supporting shapes of various sizes, punch and die mechanism for punching the shape flanges, means for centering the punch and die mechanism for shapes of different sizes, and means controlled by the punching means for clamping the shape preparatory to punching. 100
32. A machine for punching structural shapes including in combination means for supporting shapes of various sizes, punch and die mechanism for punching the shape flanges, means for centering the punch and die mechanism for shapes of different sizes, and means controlled by a distance record device for centering the punch and die mechanism for shapes of different sizes, 105
- means for traveling and stopping the shape at various desired positions, and means for clamping the shape prior to and unclamping it after each punching operation. 110
33. A machine for punching structural shapes including in combination means for supporting shapes of various sizes, punch and die mechanism for punching the shape flanges, means for centering the punch and die mechanism for shapes of different sizes, and means for clamping the shape preparatory to punching. 115
34. A machine for punching structural shapes including in combination means for supporting shapes of various sizes, punch and die mechanism for punching the shape flanges, means for centering the punch and die mechanism for shapes of different sizes, and means controlled by the punching means for clamping the shape preparatory to punching. 120
35. A machine for punching structural shapes including in combination means for supporting shapes of various sizes, punch and die mechanism for punching the shape flanges, means for centering the punch and die mechanism for shapes of different sizes, and means controlled by a distance record device for centering the punch and die mechanism for shapes of different sizes, 125
- means for traveling and stopping the shape at various desired positions, and means for clamping the shape prior to and unclamping it after each punching operation. 130

and die mechanism for punching the shape flanges, means acting automatically to center the punch and die mechanism for shapes of different sizes and means controlled by the punching means automatically clamping the shape preparatory to punching.

33. A machine for punching structural shapes including in combination means for supporting shapes of various sizes, punch and die mechanism for punching the shape flanges, means for centering the punch and die mechanism for shapes of different sizes, means for traveling and stopping the shape at various desired positions to be punched, and means controlled by the punching mechanism for clamping the shape prior to and unclamping it after each punching operation.

34. A machine for punching structural shapes including in combination means for supporting shapes of various sizes, punch and die mechanism for punching the shape flanges, means controlled by a distance record device for centering the punch and die mechanism for shapes of different sizes, means for successively traveling and stopping the shape at various positions in accordance with the indications of the distance record device, and means controlled by the punching mechanism for clamping the shape prior to and unclamping it after each punching operation.

35. A machine for punching structural shapes including in combination means for supporting shapes of various sizes, punches and dies for punching a flange, means for centering the punches and dies for various sizes of shapes, and for moving the punches and dies together and apart to symmetrically position the punches and dies on either side of the web, means for traveling and stopping the shape to be punched at various desired positions, and means controlled by the punching mechanism for clamping the shape prior to and unclamping it after each punching operation.

36. A machine for punching structural shapes including in combination means for supporting shapes of various sizes, punches and dies for punching a flange, means for centering the punches and dies for various sizes of shapes, and for moving the punches and dies together and apart to symmetrically position the punches and dies on either side of the web, a distance record device and means for traveling and successively stopping the shape to be punched in accordance with the indications of the distance record device and means controlled by the punching mechanism for clamping the shape prior to and unclamping it after each punching operation.

37. A machine for punching structural shapes including in combination means for supporting a beam on the flange edges,

punch and die mechanism for punching the beam flanges, means for centering the punch and die mechanism relatively to the webs of different size beams, and means for clamping the beam preparatory to punching.

38. A machine for punching structural shapes including in combination means for supporting a beam on the flange edges, punch and die mechanism for punching the beam flanges, means for centering the punch and die mechanism relatively to the webs of different size beams, and means controlled by the punching mechanism for clamping the beam preparatory to punching.

39. A machine for punching structural shapes including in combination means for supporting a beam on the flange edges, punch and die mechanism for punching the beam flanges and means operating automatically to move the punch and die mechanism toward and away from said support to center same relatively to the webs of different size beams and means for clamping the beam preparatory to punching.

40. A machine for punching structural shapes including in combination means for supporting a beam on the flange edges, punch and die mechanism for punching the beam flanges, means for moving the punches and dies together or apart to symmetrically position the punches on either side of the web, and means for clamping the shape preparatory to punching.

41. A machine for punching structural shapes including in combination means for supporting a beam on the flange edges, punch and die mechanism for punching the beam flanges, means for moving the punches and dies together or apart to symmetrically position the punches on either side of the web, and means controlled by the punching means for clamping the shape preparatory to punching.

42. A machine for punching structural shapes including in combination means for supporting a beam on the flange edges, punch and die mechanism for punching the beam flanges, means for centering the punch and die mechanism relatively to the webs of different size beams, and means for moving the punches and dies together or apart to symmetrically position the punches on either side of the web.

43. A machine for punching structural shapes including in combination means for supporting shapes of various sizes, a punch and die mechanism for simultaneously punching both flanges of the shape.

44. A machine for punching structural shapes including in combination means for supporting shapes of various sizes, punches and dies for both flanges of the shape and a single actuator therefor.

45. A machine for punching structural shapes including in combination means for

- supporting shapes of various sizes, punches and dies for both flanges of the shape, and a single actuator for simultaneously operating the punches for both flanges.
- 5 46. A machine for punching structural shapes including in combination means for supporting shapes of various sizes, punches and dies for both flanges of the shape and a single fluid pressure actuator therefor.
- 10 47. A machine for punching structural shapes including in combination means for supporting shapes of various sizes, punches and dies for both flanges of the shape, and a single hydraulic actuator therefor.
- 15 48. A machine for punching structural shapes including in combination means for supporting shapes of various sizes, a punch and die mechanism for simultaneously punching both flanges of the shape, and means including a distance record device for automatically controlling said punching mechanism.
- 20 49. A machine for punching structural shapes including in combination means for supporting shapes of various sizes, punches and dies for both flanges of the shape and a single actuator therefor and means including a distance record device for automatically controlling said actuator.
- 25 50. A machine for punching structural shapes including in combination means for supporting shapes of various sizes, punches and dies for both flanges of the shape, a single fluid pressure actuator therefor, and means including a distance record device for automatically controlling said actuator.
- 30 51. A machine for punching structural shapes including in combination means for supporting shapes of various sizes, a punch and die mechanism for simultaneously punching both flanges of the shape, and means for adjusting said punching mechanism for punching shapes of different sizes.
- 35 52. A machine for punching structural shapes including in combination means for supporting shapes of various sizes, punches and dies for both flanges of the shape and a single actuator therefor, and means for positioning said punches and dies toward and away from each other for punching shapes of different sizes.
- 40 53. A machine for punching structural shapes including in combination means for punching both flanges of a shape including a punch and die for each flange, means for centering said punches and dies for the respective flanges together, and means for moving them toward or from each other for beams of different sizes.
- 45 54. A machine for punching structural shapes including in combination means for punching both flanges of a shape including a punch and die for each flange, means for centering said punches and dies for the respective flanges together, means for moving them toward or from each other for beams of different sizes.
- 50 55. A machine for punching structural shapes including in combination means for supporting shapes of various sizes, punches and dies for both flanges of the shape, a single actuator for simultaneously operating the punches for both flanges, said centering and moving means being automatically operated.
- 55 56. A machine for punching structural shapes including in combination means for 70 punching both flanges of a shape including a plurality of punches and dies for each flange, means for centering all said punches and dies for shapes of different sizes, means for increasing and decreasing the distance between the punches and dies for one flange and those for the other flange for shapes of different sizes, and means for moving the punches and dies for each flange relatively to each other to symmetrically vary the position of the punches on both sides of the web.
- 60 57. A machine for punching structural shapes including in combination means for 75 punching both flanges of a shape including a plurality of punches and dies for each flange, means for centering all said punches and dies for shapes of different sizes, means for increasing and decreasing the distance between the punches and dies for one flange and those for the other flange for shapes of different sizes, and means for moving the punches and dies for each flange relatively to each other to vary the position of the punches on both sides of the web.
- 65 58. A machine for punching structural shapes including in combination means for 80 punching both flanges of a shape including a plurality of punches and dies for each flange, means for centering all said punches and dies for shapes of different sizes, means for increasing and decreasing the distance between the punches and dies for one flange and those for the other flange for shapes of different sizes, and means for moving the punches and dies for each flange relatively to each other to vary the position of the punches on both sides of the web.
- 70 59. A machine for punching structural shapes including in combination means for 85 supporting a shape horizontally on the edges of its flanges, means for punching both
- 75 60. 61. 62. 63. 64. 65. 66. 67. 68. 69. 70. 71. 72. 73. 74. 75. 76. 77. 78. 79. 80. 81. 82. 83. 84. 85. 86. 87. 88. 89. 90. 91. 92. 93. 94. 95. 96. 97. 98. 99. 100. 101. 102. 103. 104. 105. 106. 107. 108. 109. 110. 111. 112. 113. 114. 115. 116. 117. 118. 119. 120. 121. 122. 123. 124. 125. 126. 127. 128. 129. 130.

- flanges of a shape including a plurality of punches and dies for each flange, means for centering all said punches and dies for shapes of different sizes, means for increasing and decreasing the distance between the punches and dies for one flange and those for the other flange for shapes of different sizes, and means for moving the punches and dies for each flange relatively to each other 5 to symmetrically vary the position of the punches on both sides of the web.
60. A machine for punching structural shapes including in combination a punch for one shape flange, a punch for the other 10 shape flange, connections from each punch to a single actuating means, and means cooperating with said connections for increasing and decreasing the distance between said punches to accommodate shapes of different sizes.
61. A machine for punching structural shapes including in combination a punch for one flange, a punch for the other, a cylinder 15 a plunger therein, actuating connections from the cylinder to one punch and actuating connections from the plunger to the other punch.
62. A machine for punching structural shapes including in combination a punch 20 for one flange, a punch for the other, a cylinder, a plunger therein, actuating connections from the cylinder to one punch and actuating connections from the plunger to the other punch, and means for increasing 25 and decreasing the distance between the punches to accommodate shapes of different sizes.
63. A machine for punching structural shapes including in combination an actuating 30 device comprising a cylinder and a plunger therein, a reciprocable frame fixed to one member of said actuating device, a punch connected to said frame, and a punch connected to the other member of said actuating device.
64. A machine for punching structural shapes including in combination an actuating 35 device comprising a cylinder and a plunger therein, a reciprocable frame fixed to one member of said actuating device, a punch connected to said frame, and a punch connected to the other member of said actuating device, and means for increasing 40 and decreasing the distance between said punches to accommodate shapes of different sizes.
65. A machine for punching structural shapes including in combination an actuating 45 device comprising a cylinder and a plunger therein, a reciprocable frame fixed to one member of said actuating device, a punch connected to said frame, and a punch connected to the other member of said actuating device, and means for increasing 50 and decreasing the distance between said punches to accommodate shapes of different sizes.
66. A machine for punching structural shapes including in combination die blocks 55 engaging the inner faces of the opposite flanges of a beam and means for forcing said die blocks against the flanges.
67. A machine for punching structural shapes including in combination die blocks 60 engaging the inner faces of the opposite flanges of a beam and means operating just prior to the punching for forcing said die blocks against the flanges.
68. A machine for punching structural shapes including in combination die blocks 65 engaging the inner faces of the opposite flanges of a beam and means for forcing said die blocks against the flanges, said means being adjustable to act on beams of different sizes.
69. A machine for punching structural shapes including in combination die blocks 70 engaging the inner faces of the opposite flanges of a beam and a wedge for forcing said die blocks against the flanges.
70. A machine for punching structural shapes including in combination die blocks 75 engaging the inner faces of the opposite flanges of a beam and a wedge and interponents for forcing said die blocks against the flanges.
71. A machine for punching structural shapes including in combination die blocks 80 engaging the inner faces of the opposite flanges of a beam and a wedge and interponents for forcing said die blocks against the flanges said interponents being selectively introduced to accommodate beams of different sizes.
72. In a shape punching machine, a block 85 internally apertured to receive the flange of an I-beam, a longitudinally reciprocable punch mounted in the block on one side said aperture, and a co-operating die formed on the other side of said aperture.
- In testimony whereof, I have signed my name to this specification, in the presence of two subscribing witnesses.
- LOUIS A. HAWTHORNE.
- Witnesses:
- JOHN D. MORGAN,
EDWARD V. WURTS.
